UNITED STATES PATENT OFFICE.

SOLOMON H. GOLDBERG, OF WAUKEGAN, ILLINOIS.

JOINT FOR ROOFING MATERIALS.

No. 899,968.

Specification of Letters Patent.

Patented Sept. 29, 1908.

Application filed July 11, 1907. Serial No. 383,344.

To all whom it may concern:

Be it known that I, SOLOMON H. GOLDBERG, a citizen of the United States, residing at Waukegan, in the county of Lake and State of Illinois, have invented certain new and useful Improvements in Joints for Roofing Materials; and I do hereby declare the following to be a full, clear, and exact description of the invention, such as will enable others skilled in the art to which it appertains to make and use the same.

My invention relates to fastenings for roofing material in general, and especially to that class of roofing material wherein the roof is covered by a fibrous body portion which in turn is covered by a cement-like outer coating.

My invention consists in the novel nail or fastening means hereinafter disclosed.

Referring to the accompanying drawings forming a part of this specification:—Figure 1, represents the form of my invention wherein the head is shown oblong. Fig. 2, still another form, having a square head. Fig. 3, another form, having an oblong or looped head, and a modified driving portion. Fig. 4, a sectional view of a joint of roofing material, which may be fastened by any of the fastening means above mentioned. Fig. 5, a like sectional view of the old form of joint now in common use.

Referring to Fig. 2, 9 represents the point of my nail, which may be of any desired shape, and 10, the body or driving portion thereof. In Fig. 1, I have shown this point as of a flattened triangular shape, the body portion and holding portion 7, being flat in both cases. A sharp bend joins the body and holding portions, and furnishes a portion that is adapted to receive the strokes of a hammer, or other driving tool.

8 represents, in Fig. 1, the head of my nail for the purpose of holding the upper lap of the roofing material when the same is mashed down thereupon, and 11 represents a square shaped head in Fig. 2.

The form shown in Fig. 3, is provided with a point, a body and a driving portion, but the latter is provided with notches 12, and 50 the bend joining the head with the holding portion 7, is flattened, as shown in Fig. 2.

Fig. 7, illustrates a joint of roofing material consisting of flat sheets, and for which my fastenings are peculiarly adapted. In 55 this figure the lower lap 16, of the roofing material is first placed upon the roof 17, the

driving portion 2, of the nail is driven therethrough by striking upon the bend 3, above described, and the holding portion allowed to come down upon the lower lap. A further driving of the nail causes this holding portion 4, to finally come down upon the said lower lap as illustrated. In driving my fastener through this lower lap this inclined holding portion, shown in Figs. 1 and 4, first 60 contacts with the said lap at the bend where it joins the head, as above described, and the further driving of the fastener causes this bend to be extended and to therefore stretch the lap, while at the same time the flattening 65 down of the said holding portion 4, causes the said lower lap to be held in this stretched or extended condition. This inclined feature of the holding portion 7, of my nail constitutes an important feature of my invention. 70

After the nail is driven home as above described, the upper lap 18, is placed over the same as shown, and the head driven down upon the said upper lap. By this means the 80 holding portion of the nail not only stretches and holds the lap securely in position, but owing to the fact that the head is bent or driven down upon the upper lap, the said holding portion is also adapted to be thoroughly protected from the weather and therefore from rust. Since this protection from weather and rust is afforded, water is not admitted to the body or driving portion, and therefore it does not rust and cause leaks 90 in the roof as ordinarily happens in the ordinary joint, made with the ordinary nail. 95

In Fig. 8, I have illustrated the joint and nail in common use, and it can there be seen that the flat head 19, or holding portion, of the nail there shown is much more liable to rust and leak than is the holding portion 4, of my nail, and for the reason that the same is exposed and water may work its way around to the driving portion of the nail. 100

My nail may be made in any of the well known ways, out of wire, or it may be stamped out, or cut out of sheet material.

It will be seen that the holding portions taken in connection with the bends formed at 105 the juncture of the heads with said holding portions, constitute also an effective guide or gage for laying on the upper lap. That is to say, after a series of nails are driven through the lower lap all in a straight line, the parts 110 just mentioned form an effective guide for aiding the workmen to put on the upper lap

in a straight manner, for all he has to do, is to jam the edge of said upper lap over the holding portions and up against the bends described, and to then fasten down the heads. This saves time and secures a much neater and better job than would be the case, were other forms of fastenings used.

Having now described my invention, what I claim and desire to secure by Letters Patent is:—

- 10 1. A fastener for roofing material comprising a pointed flat body or driving portion; an elongated flat holding portion joined to said body portion by a bend adapted to receive the strokes of a hammer; and a head, said head joined to said holding portion by a bend adapted to permit the said head to be readily mashed down into a holding position, substantially as described.
- 15 2. A fastener for roofing material comprising a flat pointed body or driving portion; an elongated flattened holding portion joined to said body portion by a bend adapted to receive the strokes of a hammer; and a square

shaped head, said head joined to said holding portion by a bend adapted to permit the said head to be readily mashed down into a holding position, substantially as described.

3. A fastening, comprising a flattened point; a flattened body or driving portion; a flattened holding portion; and a square shaped head joined to the flat holding portion by a flattened bend in the metal, substantially as described.

4. A fastening made from a single piece of bent wire and comprising a flattened point; a flattened body or driving portion; a flattened inclined holding portion; and a square-shaped head having an opening therein joined to the flat holding portion by a flattened bend in the metal, substantially as described.

In testimony whereof, I affix my signature, in presence of two witnesses.

SOLOMON H. GOLDBERG.
